UNITED STATES PATENT OFFICE.

ALFRED HACKETT, OF TORONTO, ONTARIO, CANADA.

COMBINED THROTTLE AND REVERSING VALVE.

1,018,047.

Specification of Letters Patent.

Patented Feb. 20, 1912.

Application filed May 13, 1911. Serial No. 626,943.

To all whom it may concern:

Be it known that I, ALFRED HACKETT, a subject of the King of Great Britain, residing at the city of Toronto, in the county of 5 York, Province of Ontario, Canada, have invented certain new and useful Improvements in Combined Throttle and Reversing Valves for Motors, of which the following is a specification.

10 My invention relates to improvements in combined throttle and reversing valves for motors, and the objects of my invention are firstly: to provide a valve for the purpose set forth whereby with the use of a single 15 throttle lever, and eccentric-rod, the motor or final mover may be set in motion to any extent; checked at intermediate points, and also readily reversed; secondly: to design a type of valve which will dispense with the 20 disadvantages resulting from the great friction present in connection with the use of the ordinary D slide-valve; thirdly: to provide means for adjusting the valves in my device, each in its seat, so that while insuring 25 snug fit thereof, they will be prevented from jamming, and my preferred form of valve consists of two valves mounted in a valve-casing, the first valve controlling the passage and path of the steam, and the second valve 30 performing the function of the ordinary slide-valve in respect of controlling the ingress and egress of the steam with respect to the cylinder. Each valve is divided into two separated compartments, each compartment 35 having one or more ports which co-act with ports formed in the valve casing. A throttle-lever is provided for operating the first-mentioned valve and an eccentric-rod for the second-mentioned valve, as herein- 40 after particularly explained.

Figure 1 is a plan view of my valve. Fig. 2 is a vertical longitudinal section on the line a—b, Fig. 1, looking in the direction indicated by arrow with plain tail. Fig. 3 is a 45 vertical longitudinal section on the line a—b, Fig. 1, looking in the direction indicated by arrow with crossed tail. Fig. 4 is a vertical transverse section on the line c—d, Fig. 1. Fig. 5 is a side elevation of the reversing- 50 valve. Fig. 6 is a transverse section on the line e—f, Fig. 4, on a reduced scale, through the lower portion of the reversing-valve and its seat, and Figs. 7 and 8 are perspective views of the distributing valve operated by 55 the eccentric-rod.

In the drawings, like characters of refer-

ence indicate corresponding parts in each figure.

It will of course be understood by one skilled in this art that the ports in the distributing-valve and its seat are so placed in order to have the usual co-action so as to give a correct distribution of the steam to and from the cylinder.

A is the valve-casing provided with a 65 chamber B having intake and exhaust ports C and D. Mounted to operate within chamber B is a reversing-valve E which is divided into two separate chambers F and G by a partition H.

I is a chamber formed in the valve-casing A and in which operates the distributing-valve J. The distributing-valve J is divided into two separate chambers K and L by a partition M. The inner end of each port C 70 and D is flared as shown particularly at 2, Fig. 4, and at the outset it must be understood that the ports in the reversing-valve E will always each be in communication with its respective inner end of the said 75 ports C and D.

For the purpose of illustrating the operation of my valve, we will suppose that the port 3 in the valve E (see Fig. 6) has been moved into alignment with the port 4 in the 80 valve-casing A by the movement of the valve E through the medium of its throttle-lever 85 N. The chamber F is always full of live steam because the range of movement of the port 3 is always such as to keep this port in communicative position with respect of the inner end of the intake port C. Now the steam escapes from the port 4 through the port 5 into the chamber L, and as the port 6 of the valve J is in communication with the 90 port 7 formed in the base O of the valve-casing A, and with the port P formed in the valve-seat Q, the steam escapes through these ports into the cylinder 8 through the port 9, and so operates the piston 10. When 95 the ports 6 and 7 are open, the exhaust port 11 formed in the valve J opens into the exhaust port 12 (see Fig. 3) formed in the base O and the port R formed in the valve-seat Q, and consequently any steam there may be 100 in the cylinder 8 in front of the piston 10 escapes through the port 13 into the exhaust ports 12 and R, through the port 11 into the chamber K, thence from this chamber 105 through the exhaust port 13¹ into the exhaust port 14 whence it escapes into the chamber G of the valve E. When the port 110

3 was moved to open into the port 4, the port 15 of the valve E was moved to communicate with the port 14, and therefore free exhaust is had from the chamber G through the port 15 into the exhaust port D. In due course, the eccentric-rod 16, controlling the movement of the distributing-valve J, will have been separated so as to bring the port 17 of the valve J, into communication with the port 18 formed in the base O. The port 17 opens into the chamber L of the valve J which is filled with live-steam, consequently the live-steam escapes into the cylinder 8 through the ports 18, a, and 19 and so drives 10 the piston from dotted position back into the position illustrated in full lines. Of course as the ports 17 and 18 are opening, the ports 6 and 7 and 11 and 12 are closing. The steam in front of the piston 10, as it moves 15 from dotted position, escapes through the exhaust-port 20 into the exhaust-ports b and 21, and as the exhaust-port 22 in the valve J has been moved to communicate with the exhaust-port 21, the steam escapes into the 20 chamber K thence through the exhaust-port 13¹ into the exhaust 14 to the chamber G, whence it escapes through the exhaust-port 15 into the exhaust-port D. Now in order 25 to reverse the engine, the valve E is operated so as to bring the port 3 into communication 30 with the port 23, and the port 15 into communication with the port 24. The live steam passes through the ports 23, and 13¹ into the chamber K, and as the port 22 is supposed 35 to open into the ports 21 and b, the steam escapes from the port 20 and acts on the piston 10. When the ports 21 and 22 are open, the port 17 communicates with the ports 18, a and 19, and consequently the exhaust 40 steam escapes through these ports into the chamber L and thence through the port 5 to the port 24 and from this port through the port 15, the chamber G and thence from the port 15 to the exhaust port D. So soon 45 as the piston has reached the limit of its described movement, the port 11 communicates with the ports 12, R and 13, thus allowing live steam to escape into the cylinder 8 through these ports from the chamber K and 50 act against the piston. When the port 11 communicates with the ports 12 and R, the port 6 is in communication with the ports 7, P and 9, and consequently the exhaust steam escapes from these ports into the 55 chamber L through the port 5 into the port 24 and through these ports to the port 15 into the chamber G whence it escapes through the port 15 to the exhaust port D. It will be understood that at all times the 60 chamber F of the valve E receives the live steam, and that the chamber G of this valve receives the exhaust steam.

The eccentric-rod 16 is connected by a lever 16¹ with the stem 16² of the valve J. 65 The valve J is tapered as shown as well as

the walls of the chamber I: this construction enables me to provide a snug fit for this valve. Surrounding the valve-stem 16² is a coiled-spring 25, which is held between the cap 26 and one end of the valve J so as to hold said valve on its seat. In order to prevent the valve from jamming, I provide the following construction. Screwing through the cap 27 (secured by the screws 28 or other suitable means to the valve-casing) is a threaded-stud 29, which contacts with a block 30 held in a recess formed in the outer surface of the end 31 of the valve J. Screwing on the stud 29 is a nut 32 which locks this stud in its adjusted position. By means of the spring 25 and its associated parts, the valve J is held snugly in its seat. By screws 33 or other suitable means, the cap 26 is secured to the valve-casing. The valve E is also tapered, as well as the walls of the chamber B. The partition H is longitudinally provided with a bore 34 through the axis of the valve E. The upper end of the valve E is provided with a sleeve 35 internally threaded through 90 which passes a stud 36 which is threaded at its upper end to co-act with the threaded sleeve 35. This stud 36 projects beyond the bottom of the valve E and rests against a block 37 held in a cavity formed in the 95 bottom of the chamber B. Without further description it will be understood that by reason of the co-action between the stud 36 and block 37 while the valve E will snugly fit its seat, still it will be prevented from 100 jamming thereagainst.

38 is a cap secured by any suitable means, such as screws 39, to the top of the valve-casing A above the top of the valve E.

Surrounding the sleeve 35 and resting 105 against the valve E and housed by the cap 38, is a spring 40 which keeps this valve spring-held against its seat.

The inner end 41 of the throttle-lever N is secured by a screw 42, or other suitable 110 means, to the top of the sleeve 35.

43 and 44 are pins or stops preferably carried by the cap 38 with which the throttle-lever N is thrown into contact. When the port 3 opens into the port 4, the lever N 115 will be in contact with the pin or stop 43; and when the port 3 communicates with the port 23, the lever N will be in contact with the stop or pin 44.

Upon referring particularly to Fig. 6, it 120 will be seen that in the position of the valve E therein illustrated, the engine is throttled: only when the port 3 communicates with either of the ports 4 and 23 is steam allowed to pass into the cylinder. It is 125 therefore evident that by means of the valve E perfect control is had over the movement of the steam engine.

The ports 5 and 13¹ are always in communication with the ports co-acting there- 130

with formed in the valve-casing A. In respect of the ports 6, 7, 11 and 12, illustrated in Fig. 1, the ports in the valve J are shown larger than the ports in the valve-seat or 5 base O merely for the purpose of illustration, as will be understood.

It is now clear to one skilled in this art that the chambers K and L at different times receive live steam and exhaust steam 10 according to the direction of movement of the engine.

While I have described what I consider to be the best embodiment of my invention, I desire it to be understood that I do not confine 15 myself to the construction herein shown and described, except in so far as that may be made necessary by the requirements of the prior art and the terms of my claims.

Upon referring particularly to Figs. 1, 7, 20 and 8, it will be noticed that the ports 6 and 17 of the valve J are closer together than the ports 11 and 22, and that these pairs of ports co-act respectively with the ports 7 and 18 and 12 and 21 formed in the base O. 25 The ports 7 and 18 are farther apart than the ports 12 and 21. The ports 7 and 18 are farther apart than the ports 6 and 17, and the ports 12 and 21 are closer together than the ports 11 and 22. During movement of the distributing-valve J, it will be noticed upon referring particularly to Fig. 1, that the ports 6 and 17, when closed, are positioned between the ports 7 and 18, and that the ports 11 and 22 are, when closed, 35 positioned outside of the space separating the ports 12 and 21. In this disclosure of my invention, the said ports are placed as described as to give me the desired co-action therebetween.

40 What I claim as my invention is:—

1. A valve of the class described comprising a valve-casing provided with a first chamber provided with intake and exhaust ports, and further provided with a second- 45 chamber connected with the first-mentioned chamber by a pair of live-steam ports and a pair of exhaust-steam ports; a reversing valve mounted in the first-mentioned chamber; a partition dividing this valve into two distinct chambers, each of the said chambers 50 being provided with a port which co-acts with its respective pair of said live-steam and exhaust-steam ports, and the said chambers being further each provided with a pair of ports which co-act with ports in said 55 valve-casing whereby the ingress and egress of steam to and from a cylinder is controlled, as and for the purpose specified.

2. A valve of the class described comprising a valve-casing provided with a first- 60 chamber provided with intake and exhaust

ports, and further provided with a second-chamber connected with the first-mentioned chamber by a pair of live-steam and a pair of exhaust-steam ports, the ends of which opening into the first-mentioned chamber are spaced apart; a reversing valve mounted 70 in the first-mentioned chamber; a partition dividing this valve into two separate chambers each of which is provided with a port which operate respectively between the ends 75 of the said live-steam and exhaust-steam ports opening into the first-mentioned chamber, for the purpose set forth; a distributing-valve mounted within said second-mentioned chamber; a partition dividing this valve 80 into two distinct chambers, each of the said chambers being provided with a port which co-acts with its respective pair of said live-steam and exhaust-steam ports, and the said chambers being further each provided with a pair of ports which co-act with ports in said valve-casing whereby the ingress and egress of steam to and from a cylinder is controlled, as and for the purpose specified.

3. A valve of the class described comprising a valve-casing provided with a first-chamber provided with intake and exhaust ports, the inner end of each of which is flared as described, and further provided with a second-chamber connected with the first-mentioned chamber by a pair of live-steam and a pair of exhaust-steam ports; a reversing valve mounted in the first-mentioned chamber; a partition dividing this valve into two separate chambers each of which is provided with a port; means for limiting the range of movement of said valve so that the live-steam chamber thereof will always be in communication with said intake- port, and the exhaust- steam 90 chamber thereof will always be in communication with said exhaust port; a distributing valve mounted within said second-mentioned chamber; a partition dividing this valve into two distinct chambers, each 95 of the said chambers being provided with a port which co-acts with its respective pair of said live-steam and exhaust-steam ports, and the said chambers being further each provided with a pair of ports which co-act with ports in said valve casing whereby the ingress and egress of steam to and from the cylinder is controlled, as and for the purpose specified.

4. A valve of the class described comprising a valve-casing provided with a first-chamber provided near its upper end with intake and exhaust ports, the inner end of each of which is flared, as described, and further provided with a second - chamber connected with the first-mentioned chamber by a pair of live - steam ports and a pair of exhaust-steam ports, the upper ends of which open into the first-mentioned chamber near the bottom thereof and are 125 130

- spaced apart; a reversing valve mounted in the first-mentioned chamber; a partition dividing this valve into two separate chambers each of which is provided with a port, 5 means for limiting the range of movement of said valve so that the ports opening from the said chambers thereof can be made to register at will with the desired one of the 10 said live-steam, and the desired one of said exhaust-steam ports; a distributing - valve mounted within said second - mentioned chamber; a partition dividing this valve into two distinct chambers, each of the said chambers being provided with a port which 15 co-acts with its respective pair of said live-steam and exhaust-steam ports, and the said chambers being further each provided with a pair of ports which co-act with ports in 20 said valve-casing whereby the ingress and egress of steam to and from a cylinder is controlled, as and for the purpose specified.
5. A valve of the class described comprising a valve-casing provided with a chamber provided near its upper end with intake 25 and exhaust ports the inner ends of each of which is flared, as described, and further provided with a pair of live-steam, and exhaust-steam, ports, opening from said chamber near the bottom thereof and spaced 30 apart; a reversing valve mounted in said chamber; a partition dividing this valve into two separate chambers each of which is provided with a port, and means for limiting the range of movement of said valve so 35 that the ports opening from the said chambers thereof can be made to register, at will, with the desired one of the said live-steam, and the desired one of said exhaust-steam, ports, as and for the purpose specified.
40. 6. A valve of the class described comprising a valve-casing provided with a chamber with which communicates a pair of live-steam, and a pair of exhaust-steam, ports; a distributing-valve mounted to operate with- 45 in said chamber; a partition dividing this valve into two distinct chambers, each of the said chambers being provided with a port which co-acts with its respective pair of said live-steam and exhaust-steam ports, the said 50 chambers being further each provided with a pair of ports which co-act with ports in said valve-casing whereby the ingress and egress of steam to and from a cylinder is controlled, as and for the purpose specified.
55. 7. A valve of the class described comprising a valve-casing provided with a chamber with which communicates a pair of live-steam, and a pair of exhaust-steam, ports; a distributing - valve mounted to operate 60 within said chamber; a partition dividing this valve into two distinct chambers, each of the said chambers being provided with a port which co-acts with its respective pair of said live-steam and exhaust-steam ports, 65 the said chambers being further each pro-

vided with a pair of ports which co-act with ports in said valve-casing whereby the ingress and egress of steam to and from a cylinder is controlled, and a valve controlling the passage and path of steam to and from 70 said distributing-valve, as and for the purpose specified.

8. A valve comprising a valve-casing provided with a tapered-chamber having intake and exhaust ports; a tapered valve resting in 75 said chamber; a partition longitudinally provided with a bore, the said partition extending above the top of the valve in the form of a sleeve which is internally threaded at its upper end; a stud resting in said bore 80 and having its upper end threaded to engage with the threaded parts of said sleeve; the said stud projecting beyond the bottom of said valve and contacting with a block carried by the valve-casing at the bottom of 85 said chamber to prevent the valve from being jammed in its seat; a coiled spring surrounding the said sleeve and a cap secured to said valve-casing and above said valve and through which said sleeve extends, and 90 housing said spring, as and for the purpose specified.

9. A valve of the class described comprising a valve-casing provided with a first-chamber provided with intake and exhaust 95 ports, the inner end of each of which is flared as described, and further provided with a second-chamber connected with the first-mentioned chamber by a pair of live-steam and a pair of exhaust-steam ports; 100 a reversing valve mounted in the first-mentioned chamber; a partition dividing this valve into two separate chambers each of which is provided with a port; means for limiting the range of movement of said 105 valve so that the live-steam chamber thereof will always be in communication with said intake-port, and the exhaust-steam chamber thereof will always be in communication with said exhaust-port; a distributing- 110 valve mounted within said second-mentioned chamber; a partition dividing this valve into two distinct chambers, each of the said chambers being provided with a port which co-acts with its respective pair 115 of said live-steam and exhaust-steam ports, and the said chambers being further each provided with a pair of ports which co-act with ports in said valve-casing whereby the ingress and egress of steam to and from 120 the cylinder is controlled, one pair of the said pairs of ports of said distributing-valve being closer together than the other pair of said ports of this valve, and co-acting with a pair of the said ports in said 125 valve-casing which are wider apart than the same; this pair of ports in the said valve-casing being wider apart than the other pair of ports in said valve-casing with which co-act the second-mentioned pair of 130

ports in said distributing-valve which are wider apart than the same.

10. A valve of the class described comprising a valve-casing provided with a chamber with which communicates a pair of live-steam and a pair of exhaust-steam, ports; a distributing-valve mounted to operate within said chamber; a partition dividing this valve into two distinct chambers, each of the said chambers being provided with a port which co-acts with its respective pair of said live-steam and exhaust-steam ports, the said chambers being further each provided with a pair of ports which co-act with ports in said valve-casing whereby the ingress and egress of steam to and from a cylinder is controlled, one pair of the said pairs of ports of said distributing-valve being closer together than the other pair of said ports of this valve, and co-acting with a pair of the said ports in said valve-casing which are wider apart than the same; this pair of ports in the said valve-casing being wider apart than the other pair of ports in said valve-casing with which co-act the second-mentioned pair of ports in said distributing-valve which are wider apart than the same.

11. A valve of the class described comprising the combination of a valve-casing having a chamber provided with ports, and further provided with a second-chamber communicating with said first-chamber; a hollow cylindrical distributing-valve, mounted in said second-chamber, and provided with a transverse partition dividing the valve into two separate chambers, each of the said chambers being provided with a plurality of ports opening through the side of said valve; the said valve-casing being further provided with ports leading from said second-chamber to the engine cylinder; means, under the control of the engine, for operating said distributing-valve so that the ports therein will co-act with the ports opening into and out of said second-chamber to permit steam to do work, and a valve mounted in said first-chamber controlling the passage of steam to said distributing-valve, through the ports leading from said first-mentioned chamber to said second-chamber, as set forth.

12. A valve of the class described comprising a valve-casing provided with a chamber provided with ports leading from

a source of supply for the motive fluid, and further provided with ports leading to and from the cylinder of an engine; a hollow cylindrical distributing-valve mounted to operate in said chamber, and provided with a transverse partition dividing the valve into two separate chambers, each of the said chambers being provided with intake and exhaust ports, which co-act with the intake and exhaust ports leading to the engine cylinder; so that when steam is being received into the said engine-cylinder through one of the ports in one of said chambers formed in said distributing-valve, steam is escaping from said cylinder, through one of said ports of the other chamber of said distributing-valve diagonally placed in respect of the said one port of the said one of said chambers of said distributing-valve, into this said other chamber, and out of this said other chamber through an exhaust-port formed therein, and escaping from said valve-casing by one of said ports formed therein, and a valve controlling the passage of steam into said valve-casing.

13. A valve of the class described comprising a valve-casing provided with a chamber provided with ports leading from a source of supply for the motive fluid, and further provided with ports, grouped in pairs, leading to and from the cylinder of an engine; a hollow distributing-valve mounted to operate in said chamber; a partition dividing said valve into two distinct chambers each of which is provided with three ports, two ports in each chamber being grouped together to form a pair, and which co-act with their respective pair of ports in said casing leading to said engine cylinder, the ports in said valve on one side of said partition, according to the direction in which the engine is running, being intake ports, and the remaining ports in said valve being exhaust ports; means, under the control of the engine, for operating said distributing-valve, and a valve controlling the passage and path of motive fluid to and from said distributing-valve.

In testimony whereof I have affixed my signature in presence of two witnesses.

ALFRED HACKETT.
